Primary Examiner — Karen S Acker(74) Attorney, Agent, or Firm — Marshall, Gerstein & Borun LLP(57) CLAIM

The ornamental design for a tissue sheet with embossing pattern, as shown and described.

DESCRIPTION

The sole FIGURE is a top plan view of a tissue sheet with embossing pattern showing my new design.

The broken lines surrounding the FIGURE depict the boundaries to the claim and form no part thereof.

1 Claim, 1 Drawing Sheet(56)
